UNITED STATES PATENT OFFICE.

ALLYN CORNELL AND HIRAM C. HAZEN, OF SAN DIEGO, CALIFORNIA.

GAME.

Application filed May 17, 1921. Serial No. 470,376.

To all whom it may concern:

Be it known that we, ALLYN CORNELL and HIRAM C. HAZEN, citizens of the United States, residing at San Diego, in the county 5 of San Diego and State of California, have invented a certain new and useful Game, of which the following is a specification.

Our invention relates to games to be played by two persons in the form of or similar 10 to the game of checkers, in which a board is used divided into squares and a plurality of blocks used thereon and the objects of our invention are: first, to provide a game of this class, in which the blocks 15 which are played are of different power thus making the game highly interesting; second, to provide a game of this class in which one of the players challenges the other player by means of blocks of different 20 power; third, to provide a game of this class, in which the placing of the blocks is a matter that requires strategy on the part of the players; fourth, to provide a board which is 25 divided into squares, and also subdivided into five sub-divisions, two on each side of the middle sub-division which is the space where the players may not place their 30 blocks, in starting; fifth, to provide a novel game of this class, and a novel way of playing the game and sixth, to provide a game of this class, which is very simple, economical to construct, entertaining and instructive.

With these and other objects in view as 35 will appear hereinafter, our invention consists of certain novel features of construction, combination and arrangement of parts and portions, as will be hereinafter described in detail and particularly set forth 40 in the appended claim reference being had to the accompanying drawings and to the characters of reference thereon which form a part of this application, in which:—

Figure 1, is a plan view of the board. 45 Figs. 2 to 7 inclusive are six of the blocks with numerals 1 to 6 inclusive thereon showing varying power blocks. Figs. 8 and 9 show blocks with the words "Flage" thereon and numeral 4 which indicates the power of 50 4. Fig. 10, is a jinx block, Fig. 11, is named "Block," Fig. 12, is a block named "Bumper" and Fig. 13, a block named "Kammo" with the power of 5 thereon.

The board 1, is a rectangularly shaped 55 board made of any material desired, which is divided into ninety six squares, 48 of

which are light and 48 of which are dark, and the blocks are played on the dark squares. On each side of the board the word "Kammo-Flage," which is a fictitious word 60 evolved from the French word camouflage. The first row of squares on opposite sides is called the kammo row, and the dark squares are provided with crowns 1^a. The two middle rows of sections are set apart by 65 lines in the margin, and these two middle rows are a portion of the board where the players do not place their blocks in starting the game, and is considered the dangerous part for the players to get on. Thus it will 70 be noted that the board is divided into a middle section and two outer sections on opposite sides of this middle section.

The blocks as disclosed in Figs. 2 to 13 inclusive are made preferably of pasteboard 75 or cardboard, in squares of different colors, so that there are two sets of blocks as shown with different colors so that the opposing players play with blocks of different colors, and each player has twelve blocks 80 as shown in Figs. 2 to 13 inclusive. They are blank on one side and on the opposite side are as shown. The kammo block 2, as shown in Fig. 13, is the main block, and has the power of 5, the block 3, and 4, 85 marked "Flage" as shown in Figs. 8 and 9 are next in rank to the kammo block and have the power of 4, the numeral 4 being marked thereon. The bumper block 5, with the word Bumper printed thereon, as shown 90 in Fig. 12, has the power to remove any block challenging it, except in case the opposing bumper block is the challenger in which case both blocks are removed from the board. The bumper may challenge and remove any opposing block with the exception 95 of the jinx block 6, as shown in Fig. 10 and the block 7 as shown in Fig. 11, of the drawings. This jinx block will remove all challenging blocks including the bumper. This 100 bumper block 5 is also removed upon the first use of its challenging power. The jinx block 6 cannot challenge and if challenged by another block removes the challenger in every case. The block marked Block 7, cannot challenge and if challenged by another piece, it must be turned face up, but is otherwise immune, and unaffected. The block challenging the block 7, is not removed except in case the bumper block is the challenger, but is merely blocked or prevented 105 from moving into the square held by the

block 7. The plain numeral blocks 1 to 6 inclusive as shown in Figs. 2 to 7 inclusive have powers ranging from 1 to 6 as designated upon said block. These may challenge 5 and remove any block of lesser power than the challenging block or in case they are of equal power both blocks are removed. If the challenged block is greater in power the challenger is removed, the powers being 10 heretofore described.

The game is played as follows: Each of the players on opposite sides of the board places his blocks face down upon any of the dark squares of the first three rows 15 on his side of the board, being careful not to betray their identity or descriptive matter to his opponent. The strategy of their arrangement is of course a matter of the player's best judgement, and he will soon 20 learn to place them to get the best results. The players are permitted to make one move at a time in a diagonal course on the dark squares and begins by moving his block in any diagonal direction he desires one 25 square at a time. The player may look at the face side of his own blocks at any time by looking at the side nearest him in such a way that his opponent does not learn 30 their identity. Upon the positioning of a block next to a square or squares in which blocks of his opponent are positioned, the player may challenge the opposing block or blocks, which requires both blocks or the several involved to be turned face up, 35 whereupon the blocks with the greatest power remove the others, or in case they are equal in power all are removed. The challenges must be made one at time and may continue as long as the challenging 40 blocks are victorious. A challenge does not count as a move and is optional. The player may waive his right to move if he so desires and the other player may move. All removed blocks must be kept with their 45 face down so that their faces may not be seen during the game.

In order to win the player must move his block into the opposite or opposing kammo row with his kammo block or one 50 of his flage blocks or he must remove his

opponent's kammo block and should he challenge the opposing kammo block with his own kammo block, both are removed and the game is declared a draw.

Though we have shown and described a 55 particular construction combination and arrangement of parts and portions, we do not wish to be limited to this particular construction, combination and arrangement, but desire to include in the purview of our 60 invention the construction, combination and arrangement of parts and portions as will be hereinafter set forth in the appended claim.

It is obvious that with this game apparatus, there is provided a game which may be played by two persons, which is intensely interesting, instructive, teaching the players strategy; that the blocks being of varying powers provides for greater strategy 65 in the placing and playing of the blocks and provides a novel, entertaining parlor game.

Having thus described our invention what we claim as new and desire to secure by 70 Letters Patent is—

A game apparatus, including a game board provided with alternate and diagonally positioned light and dark squares, and a plurality of blocks adapted 80 to be positioned and moved face downwardly on said game board, the bottom faces of some of said blocks being provided with numerical inscriptions to indicate their relative powers, for removing each other 85 from the game board, the bottom faces of other blocks being provided with other characters indicating their relative power with each other and with the blocks provided with numerical inscriptions, and the bottom faces of the remaining blocks being provided with characters indicating their blocking effect against the movement of the other blocks on said game board.

In testimony whereof, we have hereunto 90 set our hands at San Diego, California this 9th day of May 1921.

ALLYN CORNELL.
HIRAM C. HAZEN.
